(57) **CLAIM**

The ornamental design for a bag tossing game target as shown and described.

DESCRIPTION

FIG. 1 is a perspective view of a bag tossing game target.

FIG. 2 is a side elevation view thereof.

FIG. 3 is a top view thereof; and,

FIG. 4 is a bottom view thereof.

The side elevation view shown in FIG. 2 is representative of the right side, left side, front, and rear views of the bag tossing game target.

The broken lines in the drawings depict portions of the bag tossing game target that form no part of the claimed design.
